(57) **CLAIM**

The ornamental design for a floor mopping head, as shown and described.

DESCRIPTION

FIG. 1 is a perspective view of a floor mopping head according to our new design;

FIG. 2 is a top plan view of the head of FIG. 1;

FIG. 3 is a bottom plan view of the head of FIG. 1.

FIG. 4 is a front elevation view of the head of FIG. 1;

FIG. 5 and is a left side elevation view of the head of FIG. 1 (the right side view being a mirror image thereof); and,

FIG. 6 is a rear elevation view of the head of FIG. 1.

The features shown in broken lines are for environmental purposes only and form no part of the claimed design.
